US0D1051710S

(12) **United States Design Patent** (10) **Patent No.:** **US D1,051,710 S**
(45) **Date of Patent:** **** Nov. 19, 2024**

(54) **RIVET NUT**

(71) Applicant: **Wei In Enterprise Co., Ltd.**, Tainan (TW)

(72) Inventor: **Ming-Che Kuo**, Tainan (TW)

(73) Assignee: **Wei In Enterprise Co., Ltd.**, Tainan (TW)

(**) Term: **15 Years**

(21) Appl. No.: **29/846,056**

(22) Filed: **Jul. 13, 2022**

(51) LOC (14) Cl. **08-08**

(52) U.S. Cl. **USPC** **D8/397**

(58) **Field of Classification Search**

(57) **CLAIM**

The ornamental design for a rivet nut as shown and described.

DESCRIPTION

FIG. 1 is a perspective view of a rivet nut showing my design.

FIG. 2 is a front elevational view thereof.

FIG. 3 is a rear elevational view thereof.

FIG. 4 is a left side elevational view thereof.

FIG. 5 is a right side elevational view thereof.

FIG. 6 is a top plan view thereof.

FIG. 7 is a bottom plan view thereof; and,

FIG. 8 is a cross-sectional view of the rivet nut taken along line 8-8 in FIG. 6.

1 Claim, 8 Drawing Sheets

US D1,051,710 S
